*P. Obert,
Motor.*

Patented Dec. 18, 1813.

The Schedule referred to the other Scales which are being sent, the
same containing a description of the word & the date of the instrument
the method of giving power motion to any machine by weight -

the frame in which the machine is built consisting of a right part & a left
proper Grahams. -

The right part of the frame consists of a timber frame having
a cross piece in the center, to receive the weight, the arms of which
are built up & made of the top of the timber frame. In the center of the
arms is a cast iron pulley, and on the top of the arms are two
small pulleys, the top pulley at the right end, & the top of the
other arm is a pulley of the same height, and through the middle
vertical frame the said shaft is the center of each frame & extends, and
a large pulley which has a band to the above mentioned weight
and between each of the said Grahams is placed a large wheel or ring
and placed over said top pulley, & a fine chain hangs from the said
wheel, and when the weight is raised, the chain hangs down, and
when raised up, the weight of the Grahams do the same, then in the said
shaft to the weight may then be reduced by a pulley, and the weight
catches hold, just and prevents the large wheel, it will not & chain, the
running back and makes time time with the weight at the right time
again.

Each of the aforementioned weights have the size of 3, 4, 5, 6, 7, 8
8 ft. which support a weight which is fixed at the center of the said
pulley. & have got round the large pulley, which will cause against the bot-
tom of the machine a front and back round pulley, and last there
- round rope is for the purpose of winding up the above mentioned weight
that are suspended to the above mentioned weights. By the combination
of the above described machinery the action of the machine is as follows
by winding up the weight slowly. At the bottom of the machine is

placed in short, repeated, irregular shafts, which turns inwards and having a
small cap which at the top and a large one at the bottom of the handle or
cane the upright shafts - the large one at the bottom being an upright
shaft with a large block of it representing a mill stone head. last. 16.
- since part of the machine is hidden behind the handle the pine
- types of the machine were applied either a mill or a trap, probably

the latter
